UNITED STATES PATENT OFFICE

2,424,507

APPARATUS FOR DRESSING INVOLUTE SURFACES ON GRINDING WHEELS

William Shotey, Dearborn, Mich.

Application February 28, 1944, Serial No. 524,222

4 Claims. (Cl. 125—11)

1

This invention is an improvement of the device shown in my United States Patent No. 1,912,410 of June 6, 1933. In that patent is shown a device for forming concave involute surfaces on grinding wheels used in finishing involute gear teeth. The device includes an arcuate member having the radius of the base circle of the involute, a tangent bar clamped on the periphery of the arcuate member in a manner to roll involutely thereon, and a dressing tool carried by the bar such that its point generates an involute. The point is positioned to lie in the plane of tangency so that it commences to generate its involute directly at the base circle. It has been found in practice that, as a result of this relationship, a fillet is formed on the wheel adjacent to the base circle of the involute.

The object of the present invention is to overcome this difficulty and is accomplished generally by starting the involute slightly inward of the base circle. For this purpose the axis of the tool is displaced slightly inward from the plane of tangency, preferably in an angular relation to that plane. A means is provided for adjusting the angle or the increment added to the involute within the base circle.

The tool carrier is mounted to be rotated from one side of the dressing wheel to the other. In the patent this rotation is exactly 180 degrees. According to the preferred embodiment of the invention, the amplitude is less than 180 degrees within the base circle in order to provide the aforementioned increments of the involute. The decrement from 180 degrees of amplitude is variable by means of adjustable stop members in the tool carrier, inasmuch as various designs of gears require varying increments to the involute.

The invention is fully disclosed by way of example in the following description and in the accompanying drawings in which:

Figure 1 is a plan view of the device.

Figure 2 is a vertical section, partly in elevation.

Figure 3 is a section on the line 3—3 of Figure 2;

Figure 4 is a section on the line 4—4 of Figure 2;

Figure 5 is an enlarged detail of Figure 2;

Figure 6 is a vertical elevation at right angles to Figure 2;

Figure 7 is a section on the line 7—7 of Figure 6, and

Figure 8 is a diagram illustrating the opera-

tion of the apparatus as viewed in the plane of Figure 6.

Reference to these views will now be made by use of like characters which are employed to designate corresponding parts throughout.

In Figure 1 is shown a base 1 on which is formed a standard 2 carrying a stud 3. On the stud are mounted a pair of spaced disks 4 which are congruent and of equal circumference.

On the stud 3 and between the disks is pivotally mounted an arm 5. A bushing 6 is fitted between the stud and the arm, and a set of roller bearings 7 is mounted between the bushing and arm. A nut 8 on the stud 3 tightens the assembly against a washer 9 on the stud, thereby fixing the disks 4 while permitting the arm to swivel as will presently be described. The disks 4 have the circumference of the root circle of the involute to be formed, and various sizes of disks are interchangeable on the stud.

Above the stud 3, the arm has a vertical slot 10 from the upper end of which extends a tapped hole 11, through the upper end of the arm. A pin 12 is slidably mounted in the slot and carries disks 13 on both ends, which project beyond the surfaces of the arm. Roller bearings are inserted between each disk and pin 12. A threaded stud 15 is screwed into the hole 11 and is adapted to bear upon the pin 12 when the latter is in an elevated position in the slot 10.

Upon the disks 4 is mounted a frame-like tangent bar 20 having a journal 21 extending laterally from its midpoint. In the initial position of the bar 20, the axis of the journal is in the plane of tangency and parallel to the central axis of the disks. Such initial position is secured, in setting the apparatus, by a pin 22 passed through a block 23 slidable in a slot 2' in the upright 2 and entering an aperture 23' in the tangent bar. The block is secured in the desired position in the slot 2' by a headed screw 22'.

The journal 21 supports a tool carrier which includes a hub 24 rotatably mounted on the journal and an arm 25 extending outwardly therefrom parallel to the axis of the hub. The outer end of the arm has a V-slot 26 whose bottom is parallel to the disks 4 and which is designed to receive a pointed dressing tool 27. A cap 28 is fastened on the grooved end of the arm 25 by

50 screws 29 and carries a set screw 30 for fixing the tool in the groove. The carrier is held rotatably on the journal 21 by a stud 31 passed through the outer end of the hub 24 and threaded into a hole 32 in the journal. A shoulder 31' of the stud clamps against the journal 21, and a

55

spring washer 30' secures the stud frictionally against the hub 24 by a key fit 32' on the stud.

The hub 24 is formed with a slot 33 transverse of the hub axis and having an extent of somewhat more than 180°. A stop pin 34 positioned in the slot is fastened radially to the journal 21. Normally the rotation of the hub on the journal would be limited by the engagement of the pin 34 by the bottom 33' of the slot at either side of the center of the bottom. The arcuate extent of the slot is preferably so related to the diameter of the pin 34 that the hub may be turned 180° from one side to the other of the wheel 40 to be dressed. This amplitude is, however, reduced by a pair of bumper screws 35 mounted in the hub 24 parallel to each other at opposite sides of the aforementioned center of the bottom 33' and adapted to pass through said bottom into the slot. Thus, the amplitude of the hub 24 is adjustably reduced below 180°, and this reduction may vary between wide limits. The adjustment of the screws 35 is secured by set screws 36 in the hub 24.

The wheel 40 to be dressed is mounted on a rotating spindle 41, and the dressing apparatus is positioned so that the point of the tool 27 lies initially at one side of the wheel and at its periphery. The screw 15 is tightened on the pin 12 so that the disks 13 clamp the tangent bar 20 on the disks 4. The arm 5 may then be oscillated manually on the bearings 1, for example by grasping the upper end thereof with the result that the clamped tangent bar 20 rolls on the disks 4 without slipping relatively thereto. Consequently any point on the tangent bar describes an involute path, and this is also true of the point of the tool 27.

With the bumpers 35 adjusted to extend slightly into the slot 33, the point 37 of the tool 27 lies slightly below the base circle of the involute or within the circumference of the disks 4, it being noted in this connection that the center of rotation of the tool carrier is in the axis of tangency, that is, in line with the points of the tangency on the disks 4, and that the entire tool 27 is at one side of the center of rotation.

The result of this arrangement, illustrated diagrammatically in Figure 8, is that the tool point commences to generate an involute a slight distance inward of the base circle. In other words, the bar 20 is adjusted so that it is tangent to the base circle where the latter is intersected by the involute to be formed. The point of the tool 27 is then positioned so that it lies entirely inward of the circle and of the line of tangency, that is, the point is not bisected by the line of tangency. This condition is illustrated in an exaggerated degree in Figure 8. A suitable device, well known in the art, is provided for feeding the wheel downwardly in small increments across the tool point in order to maintain the wheel in contact with tool during the dressing operation.

To the extent by which the wheel is fed inwardly beyond the initial position of the tool point, a flat annular surface 42 is formed on the side of the wheel at the periphery. This condition results from the fact the initial position of the tool point is a limit position beyond which the point cannot move inward of the base circle, and the wheel moving across this position of the point in the feeding direction can therefore be formed only with the flat surface 42.

The other side of the wheel is dressed in like manner after swinging the carrier 24-31 with the tool until the remaining bumper 35 stops

against the pin 34. The extended marginal portion 43 of the wheel, between the flat surfaces 42, forms the desired clearance within the base circle of the gear that is ground thereby. The radial extent of this portion is obviously determined by the extent of the feeding of the wheel across the tool point.

As previously indicated, in my prior patent, the tool commences to generate the involute exactly in the initial plane of tangency and exactly at the periphery of the wheel. Due to the fact that the actual point of the tool has some area, it is not practically possible to set the apparatus so that the tool will commence cutting the wheel exactly at its periphery. Consequently, a fillet is formed where the involute begins on the peripheral edge may be chipped. The apparatus herein described overcomes this difficulty by starting the involute at a point inward of the base circle. A perfect cut is made on the first operation, and a second cut for removing a fillet is not necessary.

Although a specific embodiment of the invention has been shown and been described, it will be understood that various alterations may be made without departure from the spirit of the invention as indicated by the appended claims.

Having fully described my invention, what I claim and desire to secure by Letters Patent is:

1. An apparatus for dressing grinding wheels, comprising a base, an arcuate member carried thereby, a tangent bar laid on the periphery of said member, an arm pivotally mounted at the center of said member, means on said arm for clamping said bar on said periphery, whereby said bar may be rolled involutely on said periphery, a journal extending laterally from said bar and having its axis in the axis of tangency, a tool carrier rotatably mounted on said journal, said carrier having a seat positioned to hold a dressing tool with its axis alongside said arcuate member, whereby the axis of said seat travels involutely with said bar, a stop member extending from the circumference of said journal, said carrier having a slot of substantially 180° transverse of the axis of said journal and receiving said stop member, and two bumpers extending from said carrier into said slot at opposite sides of said stop member to engage the latter and limit the rotation of said carrier on said journal.

2. An apparatus for dressing grinding wheels, comprising a base, an arcuate member carried thereby, a tangent bar laid on the periphery of said member, an arm pivotally mounted at the center of said member, means on said arm for clamping said bar on said periphery, whereby said bar may be rolled involutely on said periphery, a journal extending laterally from said bar and having its axis in the axis of tangency, a tool carrier rotatably mounted on said journal, said carrier having a seat positioned to hold a dressing tool with its axis alongside said arcuate member, whereby the axis of said seat travels involutely with said bar, a stop member extending from the circumference of said journal, said carrier having a slot of substantially 180° transverse of the axis of said journal and receiving said stop member, and two bumpers adjustably mounted in said carrier and extending from said carrier into said slot at opposite sides of said stop member to engage the latter and limit the rotation of said carrier on said journal.

3. An apparatus for dressing grinding wheels, comprising a base, an arcuate member carried thereby, a tangent bar laid on the periphery of said member, an arm pivotally mounted at the

center of said member, means on said arm for clamping said bar on said periphery, whereby said bar may be rolled involutely on said periphery, a journal extending laterally from said bar and having its axis in the axis of tangency, a tool carrier rotatably mounted on said bar on an axis perpendicular to said arcuate member, said carrier having a seat positioned to hold a dressing tool with its axis alongside said arcuate member, whereby the axis of said seat travels involutely with said bar, a stop member extending from the circumference of said journal, said carrier having a slot of substantially 180° transverse of the axis of said journal and receiving said stop member, and two bumpers extending from said carrier into said slot at opposite sides of said stop member to engage the latter and limit the rotation of said carrier on said journal.

4. An apparatus for dressing grinding wheels, comprising a base, an arcuate member carried thereby, a tangent bar laid on the periphery of said member, an arm pivotally mounted at the center of said member, means on said arm for

clamping said bar on said periphery, whereby said bar may be rolled involutely on said periphery, a tool carrier rotatably mounted on said bar on an axis perpendicular to said arcuate member to turn through a maximum arc of 180° , stop means for reducing the extent of rotation at either end of said arc, a pointed tool mounted in said carrier and having its point displaced from the plane of tangency slightly toward the center of said arcuate member, whereby the involute path of said point intersects the right cylindrical surface projected from the periphery of said arcuate member.
